UNITED STATES PATENT OFFICE.

ROY L. WOODARD, OF FULLERTON, CALIFORNIA.

WELL-DRILL.

1,197,882.

Specification of Letters Patent. Patented Sept. 12, 1916.

Application filed October 29, 1914. Serial No. 869,284.

To all whom it may concern:

Be it known that I, ROY L. WOODARD, a citizen of the United States, residing at Fullerton, in the county of Orange and State of California, have invented a new and useful Well-Drill, of which the following is a specification.

This invention relates to drills of that type used in forming oil wells and the like. 10 One of the objects of the present invention is to provide a drill which is detachably mounted within the well pipe or tube, said tube being utilized for the purpose of rotating the drill and being left in the well 15 after the completion of the drilling operation, it being possible to remove the drill from said tube whenever it is desired to sharpen it or whenever the drilling operation is completed.

20 A further object is to provide novel means for coupling or locking the drill to the well tube so that power may be properly transmitted from the tube to the drill during the formation of the well, additional means being employed for unlocking the drill from the tube whenever it is desired to remove said drill.

25 A further object is to provide a novel form of gripping tool for engaging the drill, so as to unlock it and for withdrawing said drill when unlocked, the same tool being also employed for lowering the drill into the tube and depositing it therein after it has been locked thereto.

30 With the foregoing and other objects in view which will appear as the description proceeds, the invention resides in the combination and arrangement of parts and in the details of construction hereinafter described 35 and claimed, it being understood that changes in the precise embodiment of the invention herein disclosed, can be made within the scope of what is claimed, without departing from the spirit of the invention.

40 In the accompanying drawings the preferred form of the invention has been shown.

In said drawings: Figure 1 is a central vertical longitudinal section through the 50 drill and the well tube coupled thereto, the manipulating tool being shown in engagement with the shank of the drill prior to the unlocking and elevating of the drill relative to the tube. Fig. 2 is a view similar

to Fig. 1 but showing the drill and its manipulating tool in elevation. Fig. 3 is an enlarged section on line A—B Fig. 1. Fig. 4 is a section on line C—D Fig. 1. Fig. 5 is a section on line E—F Fig. 1. Fig. 6 is a section on line G—H Fig. 1. Fig. 7 is a section on line I—J Fig. 1. Fig. 8 is a section on line K—L Fig. 1. Fig. 9 is a section on line M—N Fig. 1. Fig. 10 is a section on line O—P Fig. 1. Fig. 11 is a bottom plan view of the drill as viewed from the line Q—R Fig. 1. Fig. 12 is a side elevation of one of the bolt actuating slides. Fig. 13 is a front elevation thereof. Fig. 14 is a perspective view of one of the bolts controlled by said slides. Fig. 15 is a vertical longitudinal section through the lower end portion of the well tube, a portion of the drill being shown in position therein and in section. Fig. 16 is a perspective view of one of the bolts used for supporting the shank within the drill. Fig. 17 is a perspective view of the slide used in connection with said bolt. Fig. 18 is a section through one of the bolts used in connection with the drill handling tool, the actuating slide employed in connection therewith being shown in elevation. Fig. 19 is a section on line S—T Fig. 18. Fig. 20 is an end elevation of the bolt shown in Fig. 18. Fig. 21 is a view similar to Fig. 18 and showing another one of the bolts on said drill handling tool and the slide employed in connection with the bolt, only a portion of the bolt being shown. Fig. 22 is a longitudinal section through the shifting strip used in connection with the slides shown in Figs. 17, 18 and 21. Fig. 23 is a face view of said shifting strip. Fig. 24 is a section on line U—V Fig. 3. Fig. 25 is a section on line W—X Fig. 3.

Referring to the figures by characters of reference 1 designates a well tube made up of two thicknesses of pipe fitting snugly one within the other and secured together in any suitable manner, there being a reinforcing band or shoe 2 around the lower end of the tube and riveted or otherwise secured thereto, the lower edges of the pipes and band being beveled and disposed in alinement so as thus to produce a flare as shown at 3. Centering plates 4 are secured to the inner face of the tube at its lower end, each of these plates having wedge-shaped upper

ends as shown at 5 and said plate being preferably regularly spaced. In practice four of them are used, although it is to be understood that any desired number may be employed.

Formed within the tube at regularly spaced intervals are superposed annular series of apertures 6, these apertures being preferably rectangular and the corresponding apertures of the several series being disposed in vertical alinement. In practice four of these openings are provided in each series although it is to be understood that a greater or less number may be employed if preferred.

The tube thus far described constitutes the well tube and is adapted to be rotated in any suitable manner for the purpose of rotating a cutter, the tube following the cutter into the ground and being left therein after the completion of the well. In order that this procedure may be followed and the cutter or drill removed from the tube whenever it is desired to sharpen the drill, without the necessity of removing the tube from the well, it is necessary to provide a drill of novel form for use within the tube.

By referring to the drawings, it will be seen that the drill includes a cylindrical body 7 having a central longitudinal bore 8 extending throughout the length thereof, the upper end portion of the body being reduced annularly as at 9 so as to project through a packing ring 10 and being further reduced at its extremity, as shown at 11 where screw threads are provided. The packing ring 10 which may be formed of rubber or any other suitable material is interposed between a lower ring 12 and an upper ring 13, this upper ring being provided with upstanding screws 14 which bear against the lower end of a cap 15. Said cap is fitted tightly against the upper end of the body 7 and is held against rotation relative to the body in any suitable manner, as by means of one or more screws 16. The external diameter of the cap 15 is the same as that of the largest portion of the body 7, said diameter being a shade less than the internal diameter of the tube 1.

The cap 15 has a central rectangular opening 17 and communicating with this opening at opposite sides thereof are radial passages 18 in each of which is slidably mounted a bolt 19 having a reduced head 20 at its inner end. A longitudinal groove 21 is formed in the top of each bolt and is disposed below an aperture 22 formed in the top of the cap 15. Extending downwardly through each of the apertures 22 is one arm 23 of a T-shaped lever, this lever being fulcrumed, as at 24, upon the top of the cap 15. Each lever includes oppositely extending arms 25 and 26, the outer arms 26 being connected to vertically moving bolts 27 slidably

mounted within apertures 28 in the top of the cap. Thus it will be seen that when each lever is shifted so as to move the bolt 19 inwardly within the passage 18, the said lever will shift the bolt 27 downwardly to position back of the bolt 19, as shown in Fig. 1, thus securely fastening the bolt 19 in its inwardly projected position. However, when the inwardly extending arm 25 of each lever is pushed downwardly, the said lever will be actuated to first elevate the bolt 27 and to then shift the bolt 19 radially out of the opening 17.

Extending longitudinally through the body 7 are water passages 29 registering with like passages 30 within the cap 15, these passages permitting the downflow of water forced into the tube 1. Return flow of the water within the tube is prevented by the packing 10 which is expanded by upward movement of ring 12 caused by the outward movement of the inclined heads 33. As the water cannot return within the tube 1, it must necessarily flow upwardly around said tube and will thus keep the soil away from the tube to enable the tube to be rotated readily during the actuation of the drill.

Formed within the body 1 at distances apart equal to the distances between the superposed series of openings 6, are radial passages 31 designed, when the body is properly positioned within the tube 1, to register with the openings 6. In each of these passages 31 is slidably mounted a bolt such as shown in detail in Fig. 14. This bolt includes a cylindrical portion 32 from which extends a rectangular head 35. A flat rectangular stem 34 extends in the opposite direction from the cylindrical portion 32 and is provided with a rear enlargement 36. These bolts are so proportioned that, when they are projected outwardly, the cylindrical portion 32 will come against the inner surface of the tube 1 while heads 35 will project into the openings 6, thus fastening the body 7 to the tube 1. When, however, the bolts are retracted to the inner limits of their movements, the heads 35 will be withdrawn from the openings 6.

In order that the body 7 may be properly centered so as to bring the passages 31 into register with the openings 6 when the body 7 is lowered into the tube 1, triangular depressions 37 are formed within the periphery of the body 7 at its lower end, these depressions being regularly spaced and designed, during the lowering of the body 7 into the tube 1, to engage the centering plates 4 so that the upwardly converging walls of the depressions will straddle the wedge-shaped upper ends 5 of the plates 4. Thus, should the body 7 be out of its proper position when lowered, the engagement of the walls of depressions 37 with the upper

inclined faces of the plates 4 will result in the rotation of body 7 until the passages 31 have been brought into register with the openings 6 so that the heads 35 of the bolts 5 will be free to enter the openings. These plates 4 engaged by the walls of depressions 37, also act as stops to limit the downward movement of the body 7 within the tube 1.

Radially disposed passages 38 are formed 10 in the body 7 at diametrically opposed points and below the lower bolt 32, each of these passages being provided with a slide-able bolt 39, one of which has been shown in detail in Fig. 16. This bolt includes a 15 cylindrical portion 40 having a slot 41 extending therethrough while projecting from the inner end of the bolt is a head 42. When the bolt is in its innermost position, the head thereof is projected into the bore 8 20 in body 1, whereas, when the said bolts are shifted outwardly, the heads 42 are withdrawn from the bore 8. Each of the passages 38 has a groove 43 tending upwardly and downwardly thereon and within the 25 outer face of the body 7. In the upper portion of each groove is mounted a slide 44 having an obliquely disposed slot 45 extending thereinto from its outer face and inclined upwardly and inwardly, that portion 30 of the slide located at the inner end of the slot 45 being adapted to work within the slot 41 in bolt 39. Thus it will be seen that when the slide 44 is shifted upwardly, the lower inclined wall of the slot 45 will cause 35 the bolt 40 to slide outwardly away from the bore 8 whereas, when the slide 44 is moved downwardly, the upper inclined wall of its slot 45 will push against bolt 39 so as to force the head 42 inwardly into the 40 bore 8. A spring 46 bears downwardly on each slide 44 thus to cause the slide to move downwardly automatically when released.

Located in each groove 43 and below the slide 44 is a shifting strip 47 having a longitudinal slot 48 in which is mounted a guide stud 49. The lower end of the shifting strip 47 normally projects into the upper portion of one of the depressions 37. Consequently, when body 7 is lowered onto the 50 stop plates 4, certain of these plates will be engaged by the lower ends of the strips 47 and said strips will be shifted upwardly until the walls of the depressions 37 come against the stop plates 4. This upward movement of the strips 47 will result, obviously, in the elevation of the slides 44 and the shifting of the bolts 39 out of the bore 8.

Guide grooves 50 are formed within the lower end of the body 7 and are radially 60 disposed. Preferably four of these grooves are employed and the walls of each groove have guide ribs 51 thereon. These ribs are designed to project into corresponding grooves 52 formed in the sides of cutting 65 blades 53 which are slidably mounted with-

in the grooves 50 so as to move radially within the body 7. Each blade 53 has its outer end thickened, as shown at 54 and this thickened portion is beveled at the bottom as shown at 55 in Fig. 2, thus to produce an advancing or cutting edge 56. Each of the cutting blades has an outer inclined shoulder 57 designed to engage the flared lower end of the tube 1 while the blade is in use and also has its upper inner corner cut away to form an inclined shoulder 58 which, when blade 53 is in use, extends inwardly a short distance under the bore 8.

Slidably mounted within the opening 17 in cap 15 is a shank or core 59 preferably rectangular in cross section and which core extends longitudinally through the bore 8. A ring 60 is secured to the core 59 and is adapted to slide within and fit snugly against the wall of the lower portion of bore 8, this ring 60 being secured on the core in any desired manner, as by means of screws 61. The core projects downwardly below the ring 60 and between the cutting blades 53 and is provided, in its lower end, with radially disposed drilling blades 62. It is to be understood that when the core is in its lowermost position, the ring 60 bears against the shoulders 58 of the cutters 53 and shifts said cutters outwardly against the inner surface of the tube 1 with their beveled shoulders 57 under the flared portion of the tube 1. At the same time the inner vertical edges of the cutters 53 engage or practically engage the respective faces of the core 59, the blades 62 being disposed between the cutting blades 53, as shown particularly in Fig. 11. Obviously core 59 will prevent blade 53 from shifting inwardly when thus held.

When the core 59 is in its lowermost position, as described, the heads 20 of bolts 19 hereinbefore referred to, are seated within opposed sockets 63 formed in the upper end portion of the core and, consequently, it becomes impossible for the core to move upwardly accidentally within the body 7.

Formed longitudinally within each face of the core 59 is a channel 64, each channel having its lower end located close to the ring 60 while its upper end is normally 115 spaced from the cap 15 a distance equal to or greater than the distance between the ring 60 and the lower end of the core 59. These channels 64 are located directly back of and in communication with the respective series of vertically alining passages 31. Fixedly mounted along each of the channels 64 are parallel side strips 65 between which are mounted three sets of deflecting devices, one set being provided for each of the bolts 125 32 adjacent thereto. The sets are superposed and each of them includes an upper block 66 the lower end of which is inclined downwardly and inwardly as shown at 67. Under this block, which extends from one 130

side strip 65 to the other, are arranged spaced deflecting plates 68 secured to the side strips 65 and having their upper edges spaced from but parallel with the lower face 67 of the block 66 thereabove. The blocks 66 and the plates 68 project into the channels 64 as shown particularly in Fig. 1, the side strips 65 bearing against the outer face of the core 59 and extending close to the wall of the bore 8. It will be noted that the upper or outer ends of the inclined faces of the blocks 66 are cut away, as at 69 so that the outer angles or points of the plates 68 thus project outwardly beyond the outer ends of the inclined faces 67. Furthermore, it will be noted that inner or lower angles or points of the blocks 66 project beyond the inner edges of the plates 68. This will be apparent by referring to Fig. 12.

The blocks 66 are so positioned that when the core 59 is in its lowermost position, as shown in Fig. 1, the enlarged inner ends 36 of the bolts 32 will rest within the cut-away portions 69. When, however, the core 59 is elevated within the body 7, thus carrying the strips 65, blocks 66 and plates 68 therewith, the upper corners of the plates 68 will engage the enlargements 36, the shanks 34 being received between the plates 68.

This movement will result in the retraction of the heads 35 of the bolts from the openings 6, the enlargements 36 moving inwardly to positions within the channels 64 and back of the lower portions of the plates 68. When, however, the core 59 is moved downwardly within the body 7, carrying the blocks 66 and the plates 68 therewith, the beveled lower faces 67 of the blocks 66 will wedge back of the enlargements 36 and thus cause the bolts to be projected and the heads 35 to become seated within the openings 6.

Extending upwardly from the core 59 is a stem 70 having a threaded portion 71. This stem is adapted to be engaged by a handling tool of novel form which will now be described. Connected to a tube or rod 72 of any desired length is a coupling member 73 having an elongated socket 74 extending thereinto from its lower end. The lower portion of the socket is reduced to provide an inclined inner shoulder 75. A ring 76 is secured around the coupling member and has depending tongues 77 adapted to fit within corresponding recesses 78 formed within the upper edge portion of a shiftable ring 79. This shiftable ring extends around the coupling member and has a flared lower end as shown at 80, which, when the tongues 77 are seated in recesses 78, is supported above the lower end of the socket member 73. However, by lowering the ring 79 and then turning it so as to bring the tongues 77 out of recesses 78 and in engagement with the upper edge of the ring 79, the lower flared portion 80 of said

ring 79 will be held at a point below the lower end of the coupling member 73. Slidably mounted within the socket 74 is a block 81 provided with longitudinal grooves 82 in its periphery, these grooves being preferably regularly spaced. Secured within each of the grooves is a resilient arm 83 the inner or active face of which is threaded so as to grip securely the threaded portion 71 of the stem 70. The lower ends of the jaws are beveled so as to rest against the shoulder 75 and these jaws are held normally in their lowered positions by a spring 85 arranged in the socket 74 and bearing downwardly on the block 81.

Formed within the coupling member 73 and opening into the socket 74 are passages 85 and 86, the passages 85 being disposed oppositely to each other and the passages 86 being likewise disposed opposite to each other. Slidably mounted within the passages 85 are bolts 87 and additional bolts 88 are slidably mounted within the passages 86. The bolts 87 and 88 are of the same construction, each having a longitudinal slot 89. Bolts 87 are adapted to be actuated by slides 90 mounted within grooves 91 formed in the outer face of the coupling member 73, these slides 90 being similar to the slides 44 hereinbefore described and being extended through the slots 89. Springs 91 bear downwardly on the slides and serve to hold them normally pressed downwardly upon the bolts 87 while said bolts are projected to positions within the sockets 74 and under the block 81, thus to support the said block in elevated position and against the action of the compressed spring 85'. The bolts 88 are engaged by slides 92 similarly mounted in the outer face of the coupling member 73, these slides, however, being formed with diagonally disposed slots 93 inclined oppositely to the slots in the slides 90 so that the triangular nose 94 provided above each slot projects downwardly into the slot 89 in the bolt 88. See Fig. 21.

Slidably mounted under each of the slides 90 is a shifting strip 95 projecting below the coupling member 73 and another shifting strip 96 is slidably mounted under each of the slides 92 but these strips 96 do not project downwardly as far as do the strips 95. It might be stated that the bolts 88 are so positioned as to extend over the block 81 when said block is in its lowermost position, thus holding the block against upward movement. A spring 97 is provided above each of the slides 92 and operates to effect a quick return or downward movement of the slide 92 during the downward movement of its shifting strip 96.

Assuming that the drill is locked within the lower portion of the tube 1 as shown in Fig. 1 and it is desired to remove the drill for the purpose of sharpening, the

blades 53 and 62, the drill handling tool is lowered into the tube 1, block 81 being held up within the socket 74 by the bolts 87 and ring 79 being positioned as illustrated in Figs. 1 and 2. When the coupling member 73 is lowered a desired distance, the stem 70 is received within the lower portion of the socket 74 and, as the coupling member 73 continues to descend, the shifting strips 95 come into contact with cap 15 and are thus held against downward movement during the continued downward movement of the coupling member 73. This results in relative movement of the slides 90 and bolts 87 with the result that the said bolts are retracted from under block 81 and said block is shifted downwardly within socket 74 under the action of spring 85'. This causes the lower beveled ends of the jaws 84 to come into contact with the shoulder 75 with the result that said jaws are deflected inwardly so as to grip the threaded portion 71 of stem 70. Immediately subsequent to the release of the block 81 in the manner described, the other shifting strips 96 come into contact with the cap 15 and are shifted. This results in the projection of the bolts 88 inwardly to position over the block 81 so that the block is thus held against upward movement and the jaws 84 are secured in engagement with the threaded portion 71. During this operation the lower end of the coupling member 73 strikes the inner arms 25 of the T-levers, thus causing the bolts 27 to be raised from positions back of the bolts 19 and said bolts 19 to be shifted radially so as to withdraw their heads 20 from the sockets 63. As the bolts are shifted horizontally, they will obviously remain in any position to which they may be moved. Consequently when the coupling member is pulled upwardly with the jaws 84 gripping the stem 70, said stem as well as the core 59 will likewise be moved upwardly. During the first portion of the upward movement of the core, the plates 68 engage the enlarged inner-ends 36 of the bolts 32 and withdraw the bolts from the openings 6 in the manner hereinbefore described. At the same time the ring 60 is moved upwardly past the retracted bolts 39. Upon the completion of the retraction of bolts 32 and as soon as ring 60 has passed the bolts 39, the upper ends of the upper blocks 66 come against the cap 15 so that further upward movement of the coupling member 73 will result in the upward movement of the body 7 within the tube 1. As the core 59 has been withdrawn from between the blades 53, it will be apparent that as soon as the body 7 begins to move upwardly, the beveled shoulders 57 on the blades 53 will engage the flared lower end 3 of the tube so that the blades will thus be shifted inwardly under the core 59 and thus be free to

travel upwardly within the tube 1 with the body 7.

After the blades have been sharpened and it is desired to reinsert the drill within the tube 1 so as to continue the drilling operation, the ring 79 is lowered relative to ring 76 and turned so as to bring its flared lower end 80 below the lower end of the coupling member 73. After this adjustment has been effected, the body 7, which is suspended from the core 59 in the manner described, is lowered, jaws 84 still gripping the threaded portion 71 of stem 70. As the body moves downwardly within the tube 1, the depressions 37 receive the centering plates 4 and the blades 53 pass downwardly beyond the open end of the tube 1. Just prior to the completion of the seating of the body on the centering plates 4, certain of said plates engage the shifting strips 47 and the bolts 39 which have been automatically projected by spring pressed slides 44 into position under the ring 60, are thus retracted from under the ring 60. Consequently, the core 59 can then move downwardly independently of the body 7 and will enter between the inner edges of the blades 53. The engagement of the body with the plates 4 operates, as before described, to bring the passages 31 into alignment with the openings 6, so that, during this downward movement of core 59 relative to body 7, the blocks 66 will operate to project the bolts 32 outwardly into the openings 6, thereby locking the body 7 to the tube 1. As the core reaches the limit of its downward movement, the ring 79 strikes the arms 26 of the T-levers thus shifting said levers so as to throw the bolts 19 inwardly into engagement with the sockets 63, after which the bolts 27 assume positions back of the bolts 19 and lock them in engaging positions.

It will be noted that the upper bolts 32-33 are formed with beveled upper faces so that when these bolts are projected, they work against the bottom of the ring 12 and shift said ring upwardly, thus to compress the packing as hereinbefore stated.

What is claimed is:-

1. The combination with a revoluble apertured casing, of a core, a body carried by and movable relative to the core, cutting elements carried by the body, and means operated by the relative movement of the core and body for locking the body to and unlocking it from the tubular casing, said revoluble casing constituting means for driving the cutting element when the body is locked to the casing. 115

2. The combination with a revoluble well casing, a core, and a body supported by and movable relative to the core and insertible into the casing, of cutting elements carried by the body, means operated by the relative movement of the core and body for locking 120

said body to or unlocking it from the casing, and means operated by the movement of the core in one direction relative to the body for projecting the cutting elements beyond the end of the casing and radially beyond the wall of the casing.

3. The combination with a tube, of a core, a body mounted thereon and movable relative thereto, a cutting element carried by the body, means operated by the relative movement of the core and body for locking the body to or unlocking it from the tube, means for securing the core against movement relative to the tube, core gripping means, and means movable with said core gripping means for unlocking the body from the core.

4. The combination with a tube, of a body insertible thereinto, radially movable cutters carried by the body, a core connected to and shiftable longitudinally within the body, said core, when in one position, constituting means for spacing the cutters, means for locking the core against movement relative to the body, separate means for successively gripping the core and unlocking the same from the body, and means operated by the movement of the core relative to the body for locking said body to or unlocking it from the tube.

5. The combination with a tube, of a core, a cutting element at one end of the core, a body movably mounted on the core, cutting elements carried by the body, means for locking the body within the tube, means for locking the core against movement within the body, and means for successively unlocking the core from the body, shifting the core relative to the body, thereby to simultaneously withdraw the core from between the cutting elements on the body and unlock the body from the tube, and for elevating the body within the tube, said tube constituting means for shifting the cutting elements inwardly on the body during such upward movement of the body.

6. The combination with a revoluble tube having apertures, of a body insertible into the tube, radially movable bolts within the body, a core within and movable relative to the body, coöperating means upon the body and tube for shifting the bolts into register with the openings in the tube, and means operated by the relative movement of the body and core for shifting the bolts into the apertures, said bolts when seated in the apertures constituting means for transmitting motion from the tube to the body.

7. The combination with an apertured tube, of a body insertible thereinto and having end depressions in the periphery thereof, radially movable bolts carried by the body, centering means within the tube and coöperating with the walls of the depressions for shifting the body to position the

bolts in register with the apertures, a core movably mounted within the body, means for holding the core against downward movement within the body, means upon the body and coöperating with the centering means for releasing the core, and means operated by the movement of the released core relative to the body for projecting the bolts into the apertures.

8. The combination with an apertured tube, of a tubular body insertible thereinto, radially movable bolts carried by the body, cutting elements connected to the body, a core shiftable within the body and shiftable in one direction to project the bolts into the apertured tube and to project the cutting elements radially relative to the body, means for locking the core against movement relative to the body subsequent to projection of the bolts and cutting elements, means for unlocking the core from the body, and means for gripping the core to move it longitudinally of the body.

9. The combination with an apertured tube, of a tubular body insertible thereinto, cutting elements shiftable radially within one end portion of the body, a shiftable core within the body and coöperating with the cutting elements to project said elements radially relative to the body when the core is moved in one direction within the body, and means operated by the core when moved in said direction for locking the body to the apertured tube.

10. The combination with a tube, a tubular body insertible thereinto, a core shiftable within the body, and means operated by the movement of the core relative to the body for locking the body to and unlocking it from the tube, of means for locking the body to the core, a coupling member having a socket for the reception of a portion of the core, gripping elements movably mounted within the socket, means upon the coupling member and coöperating with the body for locking the gripping elements in engagement with the core, and coöperating means upon the coupling member and body for unlocking the core from the body subsequently to the coupling of the core to the said coupling member.

11. The combination with a tube, a body insertible thereinto and having water passages extending therethrough, and a core mounted for movement within the body, of cutting elements movable radially upon the bottom of the body, said core constituting means, when moved in one direction, for shifting said cutting elements radially and for spacing said elements, means operated by the core when moved in said direction for locking the body to the tube, means for locking the core against movement relative to the body subsequent to such movement, and means for successively unlocking the core

from the body, shifting the core relative to the body to release the cutting elements and unlock the body, and for lifting the body within the tube.

- 5 12. The combination with a drill including a core having a threaded stem, of a coupling member having a stem receiving socket, movably supported threaded jaws within the socket, means for locking the
- 10 jaws in elevated positions within the socket, coöperating means upon the drill and socket for releasing the jaws when the stem is positioned therebetween, means for automat-

ically shifting the released jaws, means for automatically deflecting the released jaws 15 toward each other to bind upon the stem, and means for automatically locking the jaws in engagement with the stem.

In testimony that I claim the foregoing as my own, I have hereto affixed my signature 20 in the presence of two witnesses.

ROY L. WOODARD.

Witnesses:

CARL SCHUMACHER,
JULIA L. SCHUMACHER.
